UNITED STATES PATENT OFFICE.

CARLOS FADER, OF LANDAU, GERMANY.

GAS-LIGHTING APPARATUS.

SPECIFICATION forming part of Letters Patent No. 689,866, dated December 31, 1901.

Application filed April 4, 1901. Serial No. 54,322. (No model.)

To all whom it may concern:

Be it known that I, CARLOS FADER, a subject of the German Emperor, residing at Mendoza, Argentina, actually at Landau, Bavaria, Germany, have invented new and useful Improvements in Gas-Lighting Apparatus, (for which I have applied for a patent in Germany, dated December 13, 1900, application No. F. 13,602; in France, dated January 14, 1901, application No. 295,527; in Belgium, dated January 21, 1901, application No. 122,325, and in Great Britain, dated January 25, 1901, No. 1,770,) of which the following is a specification.

15 The lighting every evening of municipal gas-lamps and the extinguishing of them at dawn at present necessitate a large number of lamplighters, which involves considerable expense. The removal of this inconvenience 20 in public lighting systems has already been repeatedly the object of inventions relating to automatic igniters, but so far without result, because they have not proved at all reliable. The introduction of electric street-lighting 25 in many towns has rendered the employment of lamplighters superfluous; but owing to the extreme cheapness of incandescent gas-lighting the illumination of the streets therewith has come again more and more into use, even 30 where there already exist electric central stations. Consequently the need is again manifest of an automatic gas-igniting system applicable to each gas-lamp, whereby it can be lighted or extinguished from the gas-works 35 by means of a momentary augmentation or reduction of the pressure of the gas in the pipes.

The present invention, which is illustrated 40 in the accompanying drawings in two forms of construction, is designed to fulfil the purpose of lighting the public gas-lamps simultaneously without further attention from the gas-works, or in case of domestic gas-lights from a pressure-regulator inserted in the gas-45 main in the house itself, and even of regulating the lights and of extinguishing some of them during the night and the rest of them simultaneously at dawn.

The gas-igniting apparatus is illustrated in 50 section in the drawings and consists of a casing A, on which is screwed a ring B, provided with a curved support and boss C. Between

the casing and the ring is fixed the edge of a flexible leather diaphragm D. On the casing A is a screw-threaded nipple e, onto which is 55 screwed an ordinary burner, or, as shown in the drawings, a Bunsen burner, F, for incandescent light. There is also on the casing a nipple g, into which is screwed either, as in Figure 1, a small gas-pipe H, on which is set 60 a revoluble spongy platinum burner J, or else, as in Fig. 2, a small gas-pipe K, which opens into a conical pipe l, attached to the Bunsen burner, so as to form within the latter an igniter-burner. In both figures, o is a cut-off 65 and pressure-regulating rod which passes through the center of the diaphragm D and boss C. This rod o is firmly connected with the diaphragm D by means of nuts and washers m. Between the diaphragm and the boss is 70 placed a counter-spring f, the tension of which can be adjusted by the regulating-screw i. The ring j at the lower end of the valve-rod o serves to control the ignition mechanism when the latter is under the day 75 pressure. The upper end of the valve-rod o is in the shape of a slender regulating-cone q, which serves to regulate the flame of the burner F with varying gas-pressure.

In Fig. 1, r is a double valve-plug, which 80 when the diaphragm D rises is moved to its seat s in the nozzle of the Bunsen burner and when it falls closes the passage in the valve-seat t. u is a stop-ring on the valve-rod o, which presses the lever h downward when the 85 diaphragm is pressed down into its lowest position, owing to the maximum pressure of gas. In Fig. 1 the valve-rod v has at its upper end the valve-plug w, which closes the aperture of the valve-seat x by the pressure 90 of the spring y. The lower end of this valve-rod v is provided with an adjustable stop a, on which rests the lever h. In Fig. 2 the valve-rod o has underneath the regulating-cone q a valve-plug z, which in the highest 95 position of the diaphragm D is moved to its seat s in the nozzle of the Bunsen burner. On this valve-rod o there is also a stop-ring u, on which the lever h rests. The valve-rod v is provided at the upper end with the valve-plug w', which opens the aperture of the valve-seat x' when the diaphragm stands in its highest position. At the lower end of the valve-rod v are two set-nuts a a, between 100

which is placed the free end of the lever *h* and over which is the spring *y*, which engages, on the other hand, under the valve-seat *x'*. The gas-igniting apparatus, with the 5 spongy platinum igniter, as shown in Fig. 1, operates in the following manner: If the burner is out of operation—that is, when the gas-cock of the lamp is turned off—the diaphragm *D* is in its highest position, and the 10 double valve-plug *r* on the valve-rod *o* closes the aperture of the valve-seat *s*. Consequently the valve-plug *w* on the valve-rod *v* also stands in its highest position and closes the aperture of the valve-seat *x*. After the 15 turning on of the gas-cock, which when the lamp has once been put into operation always remains open, the diaphragm with the day pressure still remains in position I, as the counter-spring *f*, which is adjusted to this 20 pressure, presses from below, and no gas passes to the burner *F* and the igniter *J*. As soon as the ordinary day pressure has been increased about a minute to the maximum pressure from the gas-works through the 25 town mains the diaphragm is pressed down into the lowest position III. Consequently the valve-rod *o* sinks and closes the aperture *t* by means of the double valve-plug *r*. Meanwhile the stop *u* has pressed the lever *h* and 30 the valve-rod *v* downward, whereby the valve-plug *w* opens the passage in the valve-seat *x*, so that gas passes to the igniter and ignites, owing to the catalytic properties of the spongy platinum. After this has taken place the 35 maximum pressure is adjusted from the gas-works to evening pressure, in consequence of which the diaphragm again rises into the position IV and lifts the valve-rod *o*, which opens the aperture *t*, and gas passes through 40 this and the still open passage *x* to the burner *F* and ignites at the ignition-flame. Immediately afterward the lever *h* is released and the spring *w* presses the valve-plug on the valve-seat *x*. Consequently the passage of the 45 gas is cut off and the ignition-flame is extinguished. To extinguish the lamps at dawn, the gas-pressure is reduced to the day pressure from the gas-works. Consequently the diaphragm *D* rises into the highest position 50 I and the double valve-plug *r* closes the aperture of the valve-seat *s*, and therefore cuts off the gas-supply to the burner *F*, whereupon the light is extinguished. The case of this invention is therefore the arrangement 55 of the valve-cones *z* and *r* and of placing the slight regulating-cone *q* into the passage of nozzle of the Bunsen burner. This cone *q* diminishes more or less the opening of the valve-seats for allowing more or less the access of the gas to the Bunsen burner *F* or 60 closing it, whereby the regulating-cone only regulates the quantity of gas at different gas pressures.

The gas-igniter, as illustrated in Fig. 2, 65 operates as follows: When the burner is out of operation—that is, when the gas-cock of the lamp is turned off—and it is put in operation

for the first time, the diaphragm *D* is in its highest position I, as shown in the drawings. The valve-rod *o* is also in its highest position, the valve-plug *z* being moved to its seat *s* in the nozzle of the Bunsen burner. Accordingly the lever *h* is also in its highest position on the stop *u* and the valve-rod *v* with the plug *w'*, which thus opens the aperture 75 in the valve-seat *x'*. On opening the gas-cock, which subsequently remains always open, the diaphragm with day pressure still remains in the same position I, as the counter-spring *f*, which is adjusted to this pressure, 80 presses from below. Gas now flows immediately through the passage of the valve-seat *x'* and through the tube to the small Bunsen igniter *l*, which is now ignited once and for all. As soon as the ordinary day pressure has been 85 increased from the gas-works to evening pressure the diaphragm *D* is forced down to position IV. The valve-rod *o* thereby sinks, and the valve-plug *z* opens the passage in the valve-seat *s* and allows the gas to pass to the 90 main burner *F*, which ignites at the gas-ignition flame of the small by-pass burner *l*. Meanwhile the stop *u* has released the lever *h*, whereupon the spring *y* presses down the valve-rod *v* with the plug *w'*, which closes the 95 aperture *x'*, so that the ignition-flame goes out. To extinguish the flame of the lamp, the morning pressure (from midnight to dawn) is adjusted from the gas-works to day pressure again. Hereupon the diaphragm *D* rises 100 again to its highest position, whereby the stop *u* raises the lever, and consequently the valve-rod *v*, with the valve-plug *w'*, so that the passage in the valve-seat *x'* is free, and gas passes to the small by-pass burner *l* and ignites at 105 the still burning main flame *F*, whereupon the latter goes out as the valve-plug *z* closes the passage in the valve-seat *s*.

The slender regulating-cone *q* over the valve-plugs *r* and *z* serves to regulate the 110 flame of the main Bunsen burner *F* to the gas-pressure at the time, which is effected by the diaphragm *D* correspondingly rising or falling, according as the gas-pressure is reduced or increased during the night to the 115 day and maximum evening pressure, and the passage for the gas through the valve-seat *s* is enlarged or reduced by the cone rising or sinking.

In case a number of lamps are to be extinguished during the night the spring *f* is 120 adjusted in the respective apparatuses in such a manner that they are extinguished at a pressure between the maximum evening pressure and the day pressure, which is adjusted 125 at a given time from the gas-works.

The gas-igniting apparatuses can be adapted for receiving several burners to be fitted with valves which are operated by the same diaphragm by transmitting the up-and-down 130 motion thereof to the respective valves. The device of the diaphragm *D*, with its shutting-off and regulating cone, could also be arranged so that instead of a lever *h* effecting the ig-

nition an ignition-burner is employed which burns continually.

Having now particularly described and ascertained the nature of my said invention and in what manner the same is to be performed, I declare that what I claim is—

1. The combination with a main burner, an igniter-burner and a gas-supply pipe supplying gas to both burners; of a pressure-controlled cut-off valve for the main burner, means operating automatically during the flow of gas to said burner for controlling the volume of gas supplied thereto in accordance with the variations of the pressure in the supply-pipe and a pressure-controlled cut-off valve for the igniter-burner, for the purposes set forth.

2. The combination with a main burner, an igniter-burner and a gas-supply pipe supplying gas to both burners; of a pressure-controlled cut-off valve for the main burner and a pressure-controlled cut-off valve for the igniter-burner, said valves operating to cut off the gas from both burners under a maximum pressure, to cut off the gas from the main burner and admit gas to the igniter-burner under a minimum pressure, and to admit gas to the main burner only under a normal illuminating pressure, substantially as set forth.

3. The combination with a casing provided with two tubular outlet branches, a spring-supported diaphragm in said casing, a main burner connected with one, and an igniter-burner connected with the other outlet branch; of a double-cone valve controlled by the diaphragm and controlling the flow of gas through the main-burner branch, a valve controlling the flow of gas to the igniter-burner, and a pressure-controlled lever controlling the igniter-burner valve, substantially as set forth.

4. The combination with a casing provided with two tubular outlet branches, a spring-supported diaphragm in said casing, a main burner connected with one and an igniter-burner connected with the other outlet branch; of a double-cone valve controlled by the diaphragm and controlling the flow of gas through the main-burner branch, an auxiliary valve in the outlet of the main-burner branch of the diaphragm-casing and having motion with the double-cone valve, a valve controlling the flow of gas to the igniter-burner and a pressure-controlled lever controlling the igniter-burner valve, substantially as set forth.

5. The combination with a main and an igniter burner, a supply-pipe in communica-

tion with both, a pressure-controlled main-burner cut-off valve, and a pressure-controlled igniter-burner cut-off valve; of means for arbitrarily controlling the first-named valve, for the purpose set forth.

6. In combination, a casing, a spring-supported flexible diaphragm forming within the casing a fluid-receiving chamber, a fluid-inlet and a fluid-outlet pipe leading to and from said chamber, a cut-off valve connected with the diaphragm and controlling the flow of fluid through the outlet-pipe, and a hand-operated rod connected with the diaphragm and extending therefrom and from the casing for controlling the cut-off valve, for the purpose set forth.

7. The combination with a casing, a spring-supported flexible diaphragm forming within the casing a fluid-receiving chamber, the latter having a fluid-inlet and two fluid-outlet pipes, a cut-off valve for each of said outlet pipes, one of said valves connected with the diaphragm, and a lever fulcrumed in the fluid-chamber and controlling the second cut-off valve, said lever controlled by the movements of the diaphragm through the valve-rod connected therewith; of a hand-operated rod connected with and extending from the diaphragm and casing for arbitrarily controlling both cut-off valves, for the purpose set forth.

8. The combination with a casing, a flexible diaphragm closing one end thereof, a spring acting on the outer face of the diaphragm, means for regulating the tension of said spring, a fluid-inlet and a main and an auxiliary outlet-passage for said casing, said main outlet-passage having two valve-seats 95 and ~~at~~ suitable distances apart, the double-cone valve *r* controlling the ports in said seats, the stem of said valve secured to the diaphragm and provided with a collar *u*, the taper or cone valve *q* on said stem extending through the outlet of said passage, and an auxiliary valve controlling the flow of fluid through the auxiliary outlet-passage of the casing; of the lever *k* adapted to be engaged by the aforesaid collar *u* and engaging an abutment *a* on the stem of the auxiliary valve, and a rod extending from the under side of the diaphragm, substantially as and for the purposes set forth.

In testimony whereof I have signed my name to this specification in the presence of two subscribing witnesses.
